UNITED STATES PATENT OFFICE.

JOSÉ FERENZ, OF CURITYBA, PARANA, BRAZIL.

TUBE MILL.

Application filed April 30, 1921. Serial No. 465,692.

To all whom it may concern:

Be it known that I, JOSÉ FERENZ, a citizen of Austria, but having declared my intention to become a citizen of the Republic 5 of Brazil, residing at Curityba, State of Parana, Brazil, have invented certain new and useful Improvements in Tube Mills, of which the following is a specification.

This invention relates to grinding mills 10 or machinery of the type known as ball and tube mills, the particular object of the present invention being to provide a grinding machine of the stated type in which the ball or roller will be held in a fixed position relative to the drum or tube and will be prevented from clinging to the wall of the tube. A further object of the invention is to provide a grinding machine of the stated type which may be more economically operated 15 than was possible with the machines heretofore produced. The invention is illustrated in the accompanying drawings and will be hereinafter fully described, the novel features being subsequently particularly pointed 20 out in the claim.

In the drawings—

Figure 1 is a longitudinal section showing the characteristic features of a machine embodying my present improvements;

30 Fig. 2 is an end view of the same;

Fig. 3 is a view partly in longitudinal section and partly in elevation of a complete machine embodying my improvements;

Fig. 4 is an end view thereof;

35 Fig. 5 is a view similar to Fig. 3 but showing a different embodiment of the invention;

Fig. 6 is a transverse section on the line 6—6 of Fig. 5;

40 Figs. 7 and 8 are elevations of different forms of drums or tubes in which my improvements may be embodied;

Fig. 9 is a longitudinal section illustrating another development of the invention;

45 Fig. 10 is a transverse section showing the essential elements of another form of the invention.

Reduced to its simplest form, the machine of my present invention embodies a drum or tube 1 having hollow trunnions 2 at its 50 ends and within the said drum is a roller 3 carried by a shaft 4 which projects through the hollow trunnions 2, as clearly shown. Rotation is imparted to either the roller or the drum and the material to be ground may 55 be fed into the drum through one trunnion 2 and withdrawn therefrom by suction

through the other trunnion. In Fig. 3, I have shown the drum 5 as elongated relative to the showing in Fig. 1 and equipped at one end with a swinging closure 6 to facilitate the assembling of the rollers 7 within the drum. The drum is preferably provided with internal rings 8 so that the wear upon the drum will be minimized and if any one ring should become worn through a new ring 65 may be substituted therefor without requiring the provision of a new drum as will be readily understood. At both ends of the drums are hollow trunnions 9 which are journaled in anti-friction bearings 10 provided therefor upon the upper ends of pedestals or posts 11 erected upon the floor of the workroom or upon some other substantial fixed support. The roller 7 in this form of the invention is provided in a plurality 70 of members corresponding to the rings 8 and is carried by the roller shaft 12 which extends through the hollow trunnions 9, as clearly shown, spacers 13 being provided upon the shaft between adjacent rollers, as 75 shown, so that the proper relation between the rollers and the respective rings may be maintained. In this illustration of the invention, a band pulley 14 is shown secured upon the shaft 12 near one end thereof so 80 that power may be applied thereby to rotate the rollers and the shaft is mounted at its extremities in supporting arms 15 which are pivoted at their rear ends to brackets 16 secured to a wall or other fixed support. 85

The material to be ground, which may be ore, rock, or other material, is preferably fed into the drum or tube through one of the hollow trunnions 9 and is withdrawn through the other trunnion by suction. 90 Power being applied to the pulley 14, the rollers are caused to rotate so that they roll upon the material between them and the respectively adjacent rings 8 and thereby crush the material and also effect rotation 95 of the drum so that the material is being constantly carried to and under the rollers to be crushed. While the pivotally mounted supporting arms 15 will permit a slight vertical movement of the rollers they restrain the rollers against that close adherence to the interior of the drum which occurs ordinarily under centrifugal action when the drums are rotated at high speed 100 and forms one serious objection to machines of this class as heretofore constructed. When the rollers or balls were free within 105 110

the drum, the centrifugal action which followed the rapid rotation of the drum would cause the balls or rollers to follow the surface of the drum and hence they would not 5 grind the material fed into the drum. Moreover, in order to get any grinding action at all it was necessary to employ the balls or rollers in such numbers that the weight was very heavy and a very large portion of the power applied to the machine 10 was spent in overcoming the inertia of the mass of balls or rollers. As a result of my invention, however, the grinding rollers may be much lighter than the mass of balls 15 or rollers heretofore employed and the machine may be operated at high speed, a very small proportion of the power applied to the machine being wasted in overcoming the inertia of any of the parts. This desirable 20 result is due in a large measure to the provision of the supporting arms 15 which hold the rollers at the center of gravity and tend to maintain them in operative relation to the lowest point of the inner surface of the 25 drum.

In Fig. 5, I have shown a drum 20 mounted in bearings 21 at the upper ends of pedestals 22 and provided with hollow trunnions 23 engaging in the said bearings. One of 30 the trunnions is elongated and a driving pulley 24 is secured upon the same so that in this embodiment of the invention the driving force will be applied to the drum. To one of the pedestals 22, I secure a standard 35 from the upper end of which an arm 26 extends inwardly through the respectively adjacent trunnion 23 and upon the inner extremity of this arm within the drum I provide the lug 27 in which is fixed one 40 end of a bar or rod 28 extending longitudinally within the drum and through the grinding rings 29 secured upon the inner face of the drum. It will be noted that a space, indicated at 30, is provided between 45 the innermost rings 29 and a hanger 31 extends from the shaft or rod 28 within the said space, the end of said hanger carrying the shaft 32 upon which the grinding rollers 33 are secured. If desired, the end of 50 the rod 28 opposite the end shown in the drawings may be mounted in a support corresponding to the elements 25, 26 and 27 and secured to the adjacent pedestal 22, but this specific arrangement is not necessary and, 55 as indicated by dotted lines in Fig. 5, a hanger similar to the hanger 31 may be provided at the end of the bar 28 remote from the illustrated lug 27.

The drum need not be of the true cylindrical shape illustrated in Figs. 1 to 6 but 60 may be of the stepped conical formation shown in Fig. 7 or of the form shown in Fig. 8 in which the ends 34 of the drum are conical or tapered.

The shaft carrying the grinding roller 65 need not be mounted in a fixed or swinging support as illustrated in Figs. 5 and 4, respectively, but may be equipped at its ends with links 35 upon the lower ends of which weights 36 are carried, as shown in Fig. 9. 70 It is also within the scope of my invention to employ a plurality of grinding rollers disposed in the same transverse plane of the drum and in Fig. 10 I have illustrated the drum 40 as housing a series of rollers 41 arranged in triangular relation and held in that relation by links 42.

It will be readily noted that in all the illustrated forms of the invention the grinding roller or rollers will roll or glide upon 80 the material to be ground and will not impose a lifting strain upon the driving force. The arms 15, the supporting yoke composed of the members 25, 26, 27 and 28 and the weights 36 hold the grinding roller to the 85 lowest point of the grinding drum so that the weight of the roller will be exerted constantly upon the material fed into the drum and will tend constantly to grind and crush said material, and whether the driving force 90 be applied to the drum or to the roller it is applied directly without the interposition of any train of gearing or system of belts and the waste of power in overcoming the frictional resistance of the working parts is 95 minimized. The machines may be, therefore, operated at high speed and as a result can be made in smaller dimensions for an equal load than has been heretofore possible.

Having thus described the invention, 100 what is claimed as new is:

The combination of a pair of pedestals, fixed bearings thereon, a drum disposed between said pedestals and having hollow trunnions at its ends journaled in said bearings, a standard secured on one pedestal, an arm extending from said standard through the adjacent trunnion, a bar carried by said arm and disposed longitudinally within the drum, and grinding rollers suspended from 105 said bar within the drum to co-operate with the inner surface of the drum for grinding material fed into the drum.

In testimony whereof I affix my signature.

DR. JOSÉ FERENČZ. [L.S.]
